UNITED STATES PATENT OFFICE.

SAMUEL HARP HART, OF BROWNWOOD, TEXAS.

DESIGN FOR A CUSPIDOR.

SPECIFICATION forming part of Design No. 28,387, dated March 15, 1898.

Application filed December 22, 1897. Serial No. 663,106. Term of patent 7 years.

To all whom it may concern:

Be it known that I, SAMUEL HARP HART, a citizen of the United States, residing at Brownwood, in the county of Brown and State of Texas, have invented and produced a certain new and original Design for Cuspidors; and I do declare the following to be a full, clear, and exact description of the invention, such as will enable others skilled in the art to o which it appertains to make and use the same.

My invention relates to a new and original design for cuspidors; and it consists of a cuspidor of the configuration and ornamentation shown in the accompanying drawing, in which 5 I have illustrated my invention in perspective.

The leading features of the design consist in the vessel A, the sides of which are nearly perpendicular and the extended base-supporting flange of which is in the form of a rope 20 or cable, while the upper edge is ornamented by milling. The vessel is provided with a funnel-shaped top.

What I claim is—

The design for a cuspidor, as herein shown 25 and described.

In testimony whereof I hereunto affix my signature in presence of two witnesses.

S. HARP HART.

Witnesses:

R. P. YUNN,
W. S. DANIEL.
